UNITED STATES PATENT OFFICE

2,406,291

STEAM ENGINE

Edwin S. Hall, Farmington, Conn.

Application September 9, 1943, Serial No. 501,653

11 Claims. (Cl. 121—50)

1

The invention relates to steam engines especially, and to expansible chamber engines in general. A particular object is to provide an improved steam engine of about one-third the bulk and weight of an ordinary steam engine of equivalent piston displacement, an engine capable of running two to five times faster, to deliver six to fifteen times the horsepower from a given amount of room and weight of metal. The engine is of the barrel type, having cylinders parallel to the shaft. In discussing barrel engine mechanisms, confusion has been prevalent, such terms as "swashplate" and "wabbler" having been used indiscriminantly or incorrectly. To avoid confusion, these terms are avoided, and herein a plate member inclined to and rotating with the shaft is called a "slant"; a plate member mounted on bearings on and inclined to the shaft, and having arms operably connected to the reciprocating members, is called a "starplate"; and the reciprocating members may be conveniently abbreviated to "recipers."

Another object of the invention is to provide an efficient steam engine, mechanically balanced to permit high speed, and having large ports and free flowing valves for efficient handling of the working medium at high speed, with low throttling losses and low heat losses, an engine capable of operation on an unusually low water rate, an engine in which the steam enters the cylinder at one end and exhausts at the other end of the cylinder as in a "uniflow" engine.

In such an engine, another object is to provide a balanced poppet valve, light enough to be opened and closed quickly, one having a large effective opening and excellent flow characteristics, a poppet valve axially symmetrical to the cylinder and permitting a small and symmetrical clearance volume, correctly proportioned for the optimum compression pressure when running condensing under predetermined conditions of high pressure and exhaust pressure. Another object is to provide means for automatically maintaining the clearance volume such that compression will always be substantially correct, even if operation should become non-condensing or otherwise vary from those conditions designed for. Another object is to provide effective means for blowing out condensate when warming up the engine together with automatic safety means for relieving any pressure in the engine cylinders higher than that of the high pressure steam.

Another object is to provide a cylinder whose high pressure end will stay hot, to minimize initial condensation. To this end the space around

2

the cylinder cup is evacuated. Another object is to provide construction tending to minimize heat flow from high pressure steam headers to exhaust steam headers, and in general to prevent undesirable heat flow.

Another object is to provide a practical, double-acting steam engine having no piston rods or piston rod seals, the cylinders and crosshead being combined in one member, reciprocating in the crosshead guides, the pistons being fixed. Other objects are to isolate the working medium from the lubrication oil; and to prevent, so far as practicable, passage of lubricating oil into the cylinder or of the working medium into the casing which houses the mechanism. Reciprocating cylinders, opening away from the mechanism, effectively prevent contamination of the lubricating oil by the working medium and prevent passage of lubricating oil into the working cylinders. Other objects are to provide oil control rings and drainage chambers operable to prevent oil from entering the exhaust header, the means for keeping lubricating oil separate from the working medium operating between the pressure and temperature in the casing which houses the mechanism and exhaust pressure and temperature, not between the casing conditions and those of high pressure steam.

Other objects are to provide inlet valves in the fixed pistons, pressure balanced poppet valves, of a type permitting rapid opening and closing, with free flow of the steam; to provide an improved valve gear for operating the valves, capable of controlling steam inlet from zero to maximum cutoff, forward or reverse; to use the high steam pressure as the valve spring to return the valve to its seat; and to connect the valve operating means at one end of the engine directly to that at the other end, by pull rods thru the slants, making it possible to feed always the same amount of steam in the same way to both ends of the engine from a single governor.

These and other objects of the invention will be apparent in greater detail by reference to the drawings in which

Fig. 1 is a longitudinal section of a steam engine constructed in accordance with the invention;

Fig. 2 is a transverse section substantially on the lines 2—2 of Fig. 1; and

Fig. 3 is a transverse section substantially on the line 3—3 of Fig. 1.

In the drawings, frame members 10 are held together upon crosshead guide tubes 11 by thru-bolts 12. Reciprocating members 20 are operable

in crosshead guides 11. Each reciprocator 20 is composed of a crosshead 21 and a pair of cup-shaped cylinders 22 set in the ends thereof, the spaces 25 being evacuated to discourage heat flow from cylinders 22 to crosshead 21.

Each crosshead 21 has a transverse bore 24 in which pinhead 34 is operable. Wristpin 33 is similarly operable in bushings 35 fixed in pinhead 34, and wristpin 33 is clamped by screws 32 in an arm 31 of starplate 30. The ends of wristpin 33 are spherically adapted to coat with the inner surfaces 23 of crosshead 21 to control correctly the motion of starplate 30. Wristpin 33 is adjustable axially when screws 32 are loosened.

Starplate 30 is piloted on spherical boss 41 splined to shaft 40, and starplate slippers 36, pivoted on starplate 30, are operable with film lubrication on slants 42, also splined to shaft 40.

Shaft 40 has involute splines 44 extending almost its entire length. A single key might be used instead of splines 44. Adjacent the slants 42 on shaft 40 are collars 43 which operably support and axially locate shaft 40 and its associated rotating parts in journal bearings 14. Another pair of splined sleeves 45 are also splined to shaft 40, and then the outer journal collars 46, operably supported in journal bearings 16. Nuts 47 at both ends of shaft 40 may clamp all the rotating parts solidly together, the shaft 40 serving as a splined thrubolt with nuts 47 at both ends, or with driving flange 48 integral at one end and a single nut 47 at the other end.

At each end of the engine, fixed pistons 50 are supported by cover 17. Covers 17 and 18 together form steam chest 60. Piston rings 51 are in grooves in fixed pistons 50, and oil control rings 15 are in grooves in crosshead guides 11, piston rings 51 coating with the interior cylindrical surfaces of reciprocators 20 and oil control rings 15 coating with the exterior cylindrical surfaces, both sets of rings being in substantially the same planes and traversing the same length of reciprocators 20. Oil wiped off reciprocators 20 by oil control rings 15 is drained thru drainage chambers 13.

In each of the fixed pistons 50, is a poppet valve 52, operated by bellcrank 61 and cam follower 62, the latter having a ball or roller 63 coating with cam 64. Cam 64 is axially slideable on splined sleeve 45, and is tied to another cam 64 at the other end of the engine by tie-rods 65 which pass thru collars 43, slants 42, and spherical boss 41 (in a plane at right angles to the plane of these parts in Fig. 1, as indicated in Fig. 3). Both cams 64 are operable by a governor and manual control as usual.

Poppet valve 52 looks like a sleeve and is pressure balanced, the only unbalanced area being the area of the narrow valve seat when the valve is closed. Poppet valve 52 may be "masked" or set down into a counterbored seat as shown, to permit more rapid effective opening and closing. With this type of poppet valve, clearance chamber 29 may be axially symmetrical and as small as desired for optimum compression pressure.

To adjust clearance chamber 29, displacer piston 53 is operable in cylinder member 54, and may even uncover unloading grooves 55. Outer end of displacer piston 53 is provided with dashpot piston 56 loosely operable in cylinder 69 and having valve 57 and valve spring 58. All the chambers 69 are interconnected thru conduit 66 which may be vented either to outside air or to high pressure steam in steam chest 60 by vent valve 67.

In operation, reciprocation of reciprocators 20 is accompanied by rotation of shaft 40 and its asso-

ciated parts by the operable connection of the starplate mechanism as is well known. Wristpins 33 being tangential to a circle in the plane of starplate 30, practically no torque is on starplate 30 and its motion is correctly controlled by the co-action of the spherical ends of wristpins 33 with internal surfaces 23 of crossheads 21. Oil is fed under pressure thru shaft 40, lubricating slippers 36 as they slip over slants 42, and is fed out thru arms 31 to wristpins 33, pinheads 34, and crossheads 21. Oil control rings 15, assisted by drainage chambers 13, prevent oil from passing into exhaust header chambers 19 and also prevent exhaust steam from passing inwardly into the casing formed between frame members 10.

With cams 64 in neutral position shown in Fig. 1, no steam is permitted to flow into cylinders 22 from steam chests 60. Movement of cams 64 axially in one direction will produce admission of steam for forward rotation of shaft 40 with increasingly late cutoff, while movement in the other direction produces similar action with reverse rotation of shaft 40. Cams 64 operate cam followers 63 and 62, bellcranks 61, and poppet valves 52 to admit steam to cylinders 22 in proper timed relationship for the desired operation. Steam pressure acting on cam followers 62 return them and close valves 52 after the toes of cams 64 have passed. After closing of a valve 52, the steam in cylinder 22 expands as it moves away from piston 50, until exhaust ports 26, uncover, when discharge takes place thru the exhaust header 19 to the condenser if such there be.

On return stroke of cylinder 22 compression should build up pressure less than that of the high pressure steam in steam chest 60; higher compression would lead to waste as the compressed steam surged thru valve 52 in the wrong direction, delaying inlet of high pressure steam until after cylinder 22 had started away from piston 50. To prevent this, even if operating conditions should change from those prescribed, displacer piston 53 will move away from cylinder 22 if compression pressure exceeds high pressure, increasing clearance volume 29 to prevent over-compression. Immediate return of displacer piston 53 is prevented by the dashpot action of dashpot piston 56 and its valve 57 which permits easy passage of steam into but not out of dashpot chamber 59, suspending displacer piston 53 in whatever position it is pushed by overcompression. However, since the area of the underside of dashpot piston 56 is less than its head area, steam pressure in dashpot chamber 59 will be higher than that in chamber 69, and leakage from chamber 59 to chamber 69 tends to return displacer piston 53 to its normal position with minimum clearance volume 29.

When starting a cold steam engine it is desirable to vent condensate which may form in the cylinders. Vent valve 67 may be opened to outside air whereupon steam in each cylinder 22 will push displacer piston 53 outward, uncovering unloading grooves 55 permitting flow thru piston 53 to conduit 66 and out thru valve 67. When no more condensate is discharged, valves 67 may be closed, and opened to steam chest 60, to permit high pressure steam to return displacer pistons 53 to their normal position. Displacer pistons 53 also serve as safety releases to prevent any pressure of steam or liquid in cylinders 22 from ever exceeding high steam pressure.

Having thus described the construction and operation of the invention, it is evident that the objects of the invention as stated have been attained

in a reasonable manner. While a specific embodiment of the invention has been shown and described, it is understood that changes may be made in the construction and operation of the invention without departing from the spirit or scope of the following claims.

I claim:

1. In a barrel engine mechanism, a reciprocating cylinder member having a double wall, the outer wall forming a crosshead and the inner wall forming a cylinder bore, a non-reciprocating piston operably received by said cylinder bore, and ports in the inner cylinder wall, said ports opening axially of said cylinder member into the space around said non-reciprocating piston.

2. In a barrel engine mechanism, a shaft, and reciprocating cylinder members parallel to said shaft, each of said cylinder members being double-walled and including a cylindrical crosshead operably connected to said shaft and a cup-shaped cylinder mounted in the end of said crosshead with its head and cylindrical walls spaced from the adjacent portions of said crosshead.

3. In an engine mechanism, a shaft, reciprocating cylinder members operably connected to said shaft, and fixed pistons operably received by said cylinder members, each of said cylinder members being double-walled and including a cylindrical crosshead and a cup-shaped cylinder mounted in the end of said crosshead with a cup-shaped closed chamber between said cylinder and said crosshead, said chamber evacuated to diminish heat flow from said cylinder to said crosshead.

4. In a steam engine designed to operate well under prescribed conditions of high pressure steam and condenser vacuum, a reciprocating cylinder member having a cup-shaped cylinder closed at one end and open at the other, exhaust ports at the open end of said cylinder, a non-reciprocating piston operably received by said cylinder with a certain minimum clearance volume between said piston and the closed end of said cylinder, an inlet valve coaxial with and operably mounted in said non-reciprocating piston, said cylinder and said piston and said valve so constructed that said clearance volume is axially symmetrical and small enough for optimum compression in said engine under said prescribed conditions, and means movable within said piston for increasing said clearance volume to maintain substantially optimum compression if or when operating conditions change for those prescribed.

5. In a double-acting steam engine of the barrel type having a shaft, double-ended reciprocating members parallel thereto, and mechanism operably connecting said reciprocating members to said shaft: an inlet valve system at each end of said engine, means on and rotating with said shaft for operating each inlet valve system, and tie rods parallel to said shaft and connecting one of said

means with the other to compel them to move axially in concert.

6. In a steam engine, a shaft, cylinders parallel thereto, inlet valves for admitting steam to said cylinders, and valve operating mechanism actuated to open said valves by said shaft and to close said valves by steam pressure acting on said operating mechanism as valve springs.

7. In a double-acting steam engine of the barrel type, a shaft, reciprocating members parallel to said shaft, mechanism operably connecting said reciprocating members to said shaft, a casing enclosing said mechanism, an exhaust steam chamber, and sealing means coacting with said reciprocating members to prevent the passage of oil or working medium between said casing and said chamber, said sealing means sealing between oil at no pressure and exhaust steam pressure.

8. In a steam engine, a shaft, cylinders parallel thereto, a balanced poppet valve for admitting steam to each of said cylinders, and valve mechanism operable by said shaft and including a cam and a cam follower, said cam follower movable by said cam to open said valve and movable by steam pressure to close said valve.

9. In a steam engine, a reciprocating cylinder member, a non-reciprocating piston operably received by said cylinder member, a balanced poppet valve having the form of a sleeve coaxially operable within said piston member, a sleeve member within said valve, a piston operable within said sleeve member by the difference between high steam pressure on one end thereof and compression pressure within said cylinder member on the other end thereof.

10. In a steam engine, a reciprocating cylinder member, a non-reciprocating piston operably received by said cylinder member, a balanced poppet valve having the form of a sleeve coaxially operable within said piston member, a fixed sleeve member within said valve, a smaller piston operable within said sleeve member for automatically varying the clearance volume between said cylinder member and said non-reciprocating piston, and means for moving said smaller piston to maintain substantially optimum compression in said reciprocating cylinder member.

11. In a steam engine, a reciprocating cylinder member, a non-reciprocating piston operably received by said cylinder member, a balanced poppet valve coaxially operable within said piston member, a fixed sleeve member within said valve, a smaller piston operable within said sleeve member, one end of said smaller piston engaging the pressure in said cylinder member and the other end normally engaging high steam pressure, and manually operable means for changing the pressure on said other end from high steam pressure to atmospheric pressure and vice versa to permit ready adjustment of the position of said smaller piston within said sleeve member.

EDWIN S. HALL.
